UNITED STATES PATENT OFFICE.

GEORGE W. RAPPLEYEA, OF NEW ORLEANS, LOUISIANA.

SECTIONAL-BUILT PORTABLE HOUSE.

Application filed March 14, 1927. Serial No. 175,189.

The present invention relates to a structure commonly known in the trade as a sectional built portable house; that is, a house which is assembled from pre-formed units and sections.

I am aware, of course, that it is not broadly new in this art to provide ready made frames and in fact completely assembled units, ready for erection on the premises.

For this reason, I would state that the alleged novelty in the present invention is directed to specific improvements in certain of the details, these being so made and associated with each other as to provide an exceptionally sturdy and rigid structure characterized by efficient assemblage and adaptation of each part.

An outstanding advantage of the invention, is in the corner post construction, the corner posts being recessed at its bottom and pinned to mortised sills, the arrangement being such that spreading of the parts is prevented and weight and stresses and strains evenly distributed so that the bulk of the weight is brought to bear upon sturdy concrete foundation piers, such as are provided.

A further feature of construction is derived from the use of specially designed frames, constructed to facilitate application of the weather boarding, interior wall boarding, or to facilitate mounting of windows.

A further advantage is derived from the association of the end frames at the corners of the building, which are arranged to receive the corner posts, the latter being properly bolted in place, in order to secure a rigid assembly of parts.

A further feature and advantage is derived from the provision of ledge forming strips which are carried by the sills and central stringers, in the floor construction and which serve to operate as rests for the end portions of the joists which support the sub-flooring.

A still further structural feature is a tie strip which serves to connect the upper end portions of the wall frames, together, and which cooperates with certain details in the roof construction.

Other features and advantages of the invention will become apparent from the following description and drawings.

In the accompanying drawings:

Figure 1 is a fragmentary perspective view of the outstanding features of construction, showing them in assembled relationship to clearly bring out the alleged novelty.

Figure 2 is a side elevation of a corner portion of the structure with the boarding removed.

Figure 3 is a section at right angles to Figure 2, the section being on the line 3—3 of Figure 2.

Figure 4 is an enlarged detail horizontal section on the line 4—4 of Figure 2.

Figure 5 is a section through one of the sills, showing one end of a joist resting on the ledge strip.

Figure 6 is an enlarged fragmentary perspective view showing the sill and post construction.

Figure 7 is a sectional and elevational view showing the gable roof construction.

Figure 8 is a view somewhat like Figure 5, showing how the joist cooperates with the central stringer in the floor construction.

Figure 9 is a fragmentary elevational view, showing a special bolt connection between side frames and roof.

Figure 10 is a perspective view of the special bolt.

In carrying out the invention, I employ a plurality of like frames. For instance, as shown in Figure 2, each frame is designated by the reference character 1. It is of general rectangular configuration, and comprises a pair of vertical timbers 2, central timber 3 of corresponding proportion, and connecting cross pieces 4. In addition I provide horizontal top and bottom bars 5 and 6, respectively, the bar 6 being preferably spaced above the lower end of the vertical timbers 2. These various parts are secured together in any appropriate manner, and the frame is ready made at the factory. In practice these frames are set in side by side relation and bolted together in this relationship by the bolts 7, as shown in Figure 2. However, I prefer to provide a tie strip for connecting the top portions of the frame together, this being bolted in place by an appropriate arrangement of bolts. The lower ends of the vertical timbers 2 are notched and adapted to fit over a complementary supporting sill 8, which is placed upon the concrete or brick piers 9. The sills, of course, assume the customary positions of the piers.

Attention is particularly invited to the special construction of these sills, which is shown plainly in Figure 6. In the last named figure, it will be noted that the adjacent and cooperating ends of the right angularly disposed sill 8 are notched, and the extending

portions are disposed in overlapping relation, to provide a mortised joint. Incidentally these extensions are formed with openings, and a connecting pin 9 is fitted therein. In this connection, it will be noted that the pin extends or projects above the top edges of the sill. Closely associated with the pin and the sill is the vertical corner post 11, which as before indicated is provided with a right 10 angular vertically elongated recess 12, in one corner. This recess is of a proportion to fit down over the connected end portions of the sill and when the top of the recess rests upon the upper edges of the sill, the extended portion of the pin 9 goes into a socket 13 provided for this purpose. The recess 12 is accurately proportioned with respect to the sides of the sill, so that the corner posts may rest down on the concrete pier as shown, for 15 instance, in Figure 3. In this way, the sills are tied together and the post is coupled to them, and part of the weight from the post is on the sills and part on the concrete piers. Consequently, it is uniformly distributed, and 20 strain and breakage is decidedly lessened.

Attention is invited to Figure 4, wherein it will be seen that a corner construction of the building is shown. As is obvious, the end-most frames 1, on the respective side walls of 25 the building are arranged in the relationship shown, in order to accommodate the square post. Both the bottom and the top bolts 14 and 15 are passed through the vertical end timbers of the respective frames 1, and the 30 post 11. They are arranged in intersecting relation to provide a good tight joint. Of course, an appropriate cornice 15 is provided here to conceal the meeting edges of the parts and to provide a weather proof joint.

Considering now the construction of the 35 floor, it will be seen that the customary central stringer 16 (see Figure 1) is provided and extending from opposite sides of this at right angles thereto are the joists 17. Considering 40 these parts carefully, it will be noted that on opposite longitudinal sides are ledge strips 18, and above these are small vertical cleats 19, the cleats being arranged in pairs to provide sprockets for reception of the adjacent end of 45 the joist. This same arrangement of details serves to provide a means for guiding the joists so that they are uniformly spaced apart, 50 properly distributed and readily assembled.

By directing attention now to Figure 5, it 55 will be seen that appropriate supporting blocks or strips 20 are fastened to the inner sides of the sills 88 in such position as to raise the upper edges of the joist 17 to the approximate elevation shown. This arrangement, it 60 is believed, transfers the stress and strain in a manner to prevent outward pushing of the sills from the weight of the flooring. In the drawings, I have merely shown the subflooring 21 which may be of any appropriate construction.

The construction of the roof is along the customary lines of construction. As observed in Figure 1, for instance, I show a gable roof construction, which includes central ridge piece with inclined beams 23 extending downwardly therefrom and connecting with horizontal rafters 24. In this connection, it will be noted that the lower ends of the beams are cut to provide appropriate joints. Moreover the outer ends of the rafters rest upon 70 the aforesaid tie strip which is bolted to the top bars of the aforesaid frame. If desired, a facing and frieze forming board 25 may be employed and nailed over the meeting edges of the tie strips and top bars of the frames to 75 conceal these. Also, in order to insure tight connection between the beams and the tie strips, I provide L-shaped connecting bolts 26 which assume the relationship shown in Figure 9. The rafters and beams are connected together by vertical struts 27 and diagonal bracing presses 28. Moreover the beams 23 are provided with small cleats 29 with which the purlins 30 are connected. The sheathing boards 31 are laid in the customary manner, 80 and the shingles 32 are fastened thereto as usual. Of course, to complete the exterior of the roof construction, a ridge cap 33 is provided at the apex.

In finishing off the frame work, weather 90 boards 34 are nailed to the exterior side of the aforesaid frames 1, windows 35 are arranged at appropriate points. In addition, wall and ceiling boards 36 are fastened to the inner side of the frame and are joined together by panels 37. Customary wash boards 38 and molding 39 are provided at the bottom. It is particular advantageous in making a frame of a construction ready for 95 erection, nailing the weather board on the outside, the wall board on the inside and so constructing the frame to dispose the braces and parts thereof in a position to permit windows to be mounted in the proper frame, whereby an entire section comprising weather 100 boards, windows, wall boards, and trim may be furnished ready for installing.

While it is of no unusual importance, I prefer to employ an outside casing board as indicated at 40, (see Figure 1), this being 105 informed with an apron 41. This board goes against the sill and lower weather board to conceal the joint structure and to give the outside of the structure a pleasing appearance.

Before concluding the description, I wish to point out that corner post constructions, such as are employed at the present day by the majority of builders consist of a simple four by four timber which is bolted to the outside walls, the sills abutting up against the corner posts. Because of the weight on the floor joists the joists have a tendency to push the sill outward or away from the building. This is prevented, in a measure, by the 115 120 125

outside wall sections which are bolted to the corner posts, but this places an undue strain on the bolt and is a weak point in the design of sectional built portable houses. The improvement referred to in the outset of the description locks the sills and prevents them from being spreaded or pushed out from the building. It permits the sills to meet, and they can therefore be mortised and notched together and thereby makes a much more rigid and dependable joint construction. In the past, if the sills were jointed or notched, the corner post had to set on top of the sills, and if the corner post set on the foundation, then the sill could not meet. This improvement makes an interlocking corner post which securely locks the sills in place and prevents strain or outward bulging. It also eliminates the use of tie rods and turn buckles for tying the sills together.

It is believed that by considering the description in connection with the drawing, a clear understanding of the invention will be had. Therefore, a more lengthy description is thought unnecessary.

Minor changes coming within the field of invention claimed may be resorted to, if desired.

I claim:

1. In a structure of the class described, in combination, a supporting pier, a pair of right angularly disposed sills having their adjacent ends notched to provide extensions,

said extensions being disposed in overlapping and interconnected relation, and a vertically extending post resting partly on said pier and partly on said sill, and having a recess for accommodating adjacent end portions of said sills.

2. In a structure of the class described, in combination, a supporting pier, a pair of right angularly extending sills having their adjacent ends notched to provide extensions, and to form interlocking connections, a connecting pin extending through the respective extensions and projecting above the upper edges of the sills, a vertically extending post having its lower end resting on said pier, and having a recess on one side forming a pocket for reception of adjacent end portions of the sills, said post having an additional socket receiving the upper projecting end of said pin, whereby said sills and posts are tied together and the stress and strain equally distributed.

3. In a structure of the class described, a pair of side wall frames having adjacent end timbers disposed at right angles to each other; a corner post fitted for contact with said timbers and to occupy the space therebetween, intersecting connecting bolts passing through the post and the vertical end timbers of the respective frames for connecting the three parts together.

In testimony whereof I affix my signature.
GEORGE W. RAPPLEYEA.
